STEAM BOILER REGULATOR

Filed Aug. 25, 1939

UNITED STATES PATENT OFFICE

2,245,914

STEAM BOILER REGULATOR

James W. Harrie, Oakland, Calif., assignor to
 Westinghouse Pacific Coast Brake Company,
 Emeryville, Calif., a corporation of California

Application August 25, 1939, Serial No. 291,908

1 Claim. (Cl. 236—21)

This invention relates to furnace control systems for regulating the supply of fluid fuel, such as gas or oil, to the burner of a furnace for heating a steam boiler, the present application being a continuation in part of my prior application filed in the United States Patent Office on January 6, 1938, Serial No. 183,670, which has matured into Patent No. 2,176,132.

In the operation of a boiler having a low water cut-off valve by operation of which fluid fuel supplied to the burners is automatically shut off when the water level in the boiler falls to a dangerously low point, the use of a steam pressure actuated controller for automatic regulation of the boiler fire in accordance with boiler pressure is sometimes accompanied by an undesirable condition when the water level is restored and the cut-off valve in the fuel supply line is again opened. When the fuel supply is shut off by operation of the low water cut-off valve, the steam pressure naturally falls, causing the steam pressure actuated controller to move toward its full fire position, and as a result, when the normal water level is restored and the low water cut-off valve reestablishes the supply of fuel, the fuel valve which is controlled by the steam pressure actuated controller will be in a wide open position. The fuel entering the furnace suddenly through this wide open valve may then create an explosive increase in the fire which is dangerous and detrimental to the furnace.

The principal object of this invention is to provide an improved regulator device adapted for association with a boiler having the above described equipment, which regulator device is automatically responsive to a predetermined reduction in the pressure of fuel being supplied to the boiler furnace for effecting operation of the steam pressure actuated controller to a low fire position, so that upon restoration of the normal water level and consequent opening of the low water shut-off valve the controller is initially effective to retard the supply of fuel, with the result that the furnace fire is increased gradually and at a safe rate.

Another object of the invention is to provide an auxiliary regulator of the above type, the elements of which are associated in a unitary structure adapted to be mounted in any desired position, and which device includes a manually releasable trigger mechanism adapted for operation to lock the steam actuated controller in its low fire position, following a reduction in the supply of fuel such as that effected in response to a low water condition.

Other objects and advantages of the invention will be apparent in the following more detailed description thereof, taken in connection with the accompanying drawing, wherein—

Fig. 1 is a fragmentary diagrammatic view, partly in section, of a boiler furnace equipped with a control system embodying the invention;

Fig. 2 is an enlarged detail sectional view of the steam actuated controller shown in Fig. 1 and having associated therewith an auxiliary regulator device constructed in accordance with the invention.

Referring to Fig. 1 of the drawing, there is shown therein a furnace 1, which may be of any well known construction and is provided with a fire box having a burner for heating a boiler, not shown. The burner of the furnace is adapted to be supplied with fluid fuel, such as gas or oil, through a supply pipe 3. Air is supplied to the furnace fire box through an opening controlled by a draft door 5, and the burned gases escape from the fire box through a smoke pipe 6, in which is mounted a damper 7 for regulating the rate of flow of gas through the smoke pipe.

Mounted on the furnace 1 is a steam actuated controller device 10, which may be of any suitable type operative to regulate the rate of supply of fuel through the supply pipe 3 to the furnace and also to control the draft door 5 and damper 7, which device is illustrated in the drawing as having the same construction as that disclosed in my United States Patent 2,147,294, issued on February 14, 1939. According to the present invention, the steam actuated controller 10 has associated therewith an auxiliary regulator device 11, which is operative to control operation of the controller device 10 in response to a predetermined reduction in the pressure of fuel supplied through the pipe 3, as hereinafter explained.

The furnace 1 also has associated therewith means responsive to the level of the water in the boiler of the furnace for controlling the supply of water to the boiler and the rate of supply of fuel through the supply pipe 3 to the fire box burner. As illustrated in the drawing, this means may comprise a pressure generator 12 adapted to vary the pressure of fluid in a pipe 16, a fluid pressure responsive water valve device 14 operative on a predetermined increase in fluid pressure in the pipe 16 to open a communication through a pipe 15 for supplying water to the boiler, and a fuel shut-off valve device 18 responsive to an increase in the pressure of fluid in the pipe 16 to reduce the rate of fuel flow through the supply

pipe 3. The steam generator 12 and pressure responsive valve devices 14 and 18, being well known in the art, are not illustrated in detail, but it will be understood that the generator is operative under a low water condition of the boiler to effect an increase in the pressure of fluid in the pipe 16 above a normal value, and that the valve devices 14 and 18 are operative in accordance with such increase in fluid pressure to supply water to the boiler and to reduce the supply of fuel to the burner.

As shown in Fig. 2 of the drawing, the steam pressure actuated controller device 10 comprises a movable abutment or piston 20 which is movably mounted in a bore formed in a body 21, and has secured thereto a piston stem 22 which extends through a suitably sealed opening in the end wall of the bore. Referring again to Fig. 1, the outer end of the stem 22 is connected by means of a chain 23 with a lever 24, which is pivotally supported by a pin 26 on a bracket 27 carried by the furnace 1. The lever 24 has secured thereto a weight 28 which urges the lever 24 in a clockwise direction about the pin 26 and thus exerts a downward pull through the medium of the chain 23 on the piston within the controller. The lever 24 is connected by means of a link 30 with an arm 32 associated with a valve device 33, which is interposed in the supply 3 at a point intermediate the valve device 18 and the burner of the furnace. The valve device 33 is adapted to reduce the supply of fuel to the supply pipe 3 in response to upward movement of the arm 32, link 39, and chain 23 by operation of the controller piston as hereinafter explained. The lever 24 is also connected by means of a chain 34 with the draft door 5, and by means of a chain 36 with an operating lever 37 controlling the damper 7. A weight 38 is secured to the free end of the lever 37 for exerting a force opposing the pull transmitted by the controller 10 through the medium of the chain 36, and for biasing the damper toward full open position as shown in the drawing.

As shown in Fig. 2 of the drawing, the controller device 10 further comprises valve means indicated generally by the reference character 40 for regulating the supply of fluid under pressure to a chamber 41 at the lower face of the piston 20, and for also regulating the release of fluid under pressure from that chamber. The valve means 40 includes a body having a chamber 42, which is constantly connected by way of a pipe 43 with a source of water or other fluid under pressure, and a chamber 44 which is constantly connected with the chamber 41 by way of a passage having a restricted portion 45. A ball valve 46 is disposed in the chamber 42 and is adapted to engage a seat adjacent the chamber 44 to cut off communication between chambers 42 and 44. A spring 48 is provided in chamber 42 for pressing the ball valve 46 toward seated position. Associated with the ball valve is a valve stem 59, the lower end of which extends into the chamber 44 and has formed therein a passage 51 opening at a terminal seat formed on the stem and engageable with the upper surface of the ball valve 46 to prevent flow of fluid from the chamber 44 to the passage 51.

Also formed in the body of the valve means 40 is a release chamber 53 through which the valve stem 50 extends, suitable packing being provided for the stem to prevent communication between the chamber 53 and the chamber 44. A coil spring 54 is mounted in the chamber 53 be-

tween a flange 55 on the valve stem 50 and a packing gland forming an end wall of the chamber, which spring is adapted to press the valve stem 50 upwardly, as viewed in the drawing. 5 The passage 51 in the end portion of the valve stem 50 is open to the release chamber 53, and the chamber 53 is in turn constantly connected to a drain pipe 56, which leads to a valve chamber formed in the auxiliary regulator device 11 hereinafter described. The chamber 57 at the upper face of the actuator piston 20 is constantly connected to a drain pipe 58.

For controlling operation of the valve means 40 to effect movement of the piston 20 in accordance with variations in the pressure of the steam in the boiler, the control device 10 is provided with a movable abutment in the form of a diaphragm 60, which is clamped between a cover 61 and a body 62 which is disposed above the body 21 and may be secured thereto by suitable means, such as bolts. The diaphragm 60 and cover 61 define a chamber 64 which is constantly connected by way of a pipe 65 to the boiler associated with the furnace 1 shown in Fig. 1 of the drawing. The diaphragm 60 has at the lower face thereof a follower member 67, which is urged upwardly against the diaphragm in opposition to the pressure of steam in the chamber 64 by the force of a coil spring 68 interposed between the member and a spring seat 69 adjustably supported on a threaded member 70 carried by the body 62. Operatively connected to the follower member 67 is a push rod 75 which extends through a central aperture formed in the lower spring seat 69 and through a bore in the member 70 into operative alignment with a lever 72 having one end pivotally supported by means of ball bearings 73 on a bracket 14 forming part of the frame structure of the controller device 10.

The lever 72 has mounted thereon intermediate its ends an adjusting screw 78, the end of which extends into a socket formed in one end of a rod 79, the other end of which has a socket for receiving the upper end of valve stem 50. On the free end of the lever 72 is mounted an adjusting screw 81 engaging in a socket formed in a spring seat 82, which has a tubular extension containing a coil spring 83 that is interposed between the spring seat 82 and a slidably mounted spring seat 85 which is in turn pivotally supported on one arm of a bell crank lever 87 journaled on a pin 88 carried by the bracket 74. The other arm of the bell crank lever 87 is offset and carries a roller 90 which is adapted to ride on an inclined rod 91 adjustably secured to a vertically disposed rod 93 by suitable means, including an adjusting screw 94 and bracket 96. The rod 93 is adapted to be guided by a roller 98 which is suitably journaled on a pin carried by the bracket 74, the lower end of the rod being secured to an arm 99 carried by the piston stem 22.

According to my invention, the auxiliary regulator device 11 comprises a frame 100 of polygonal form having a bottom portion 102 on which are suitably mounted a supply valve assembly 103 and a drain valve assembly 104, and a casing member 105 which is secured to the upper portion of the frame by means of a clamping member 107. The member 107 extends through a suitable aperture 108 formed in the frame and a similar aperture 109 formed in the casing member and into a chamber 110 therein which contains a nut 111 having screw threaded engage-

ment with the clamping member. Suitable mounting lugs 113 having apertures for receiving bolts are formed on the casing 105.

A flexible diaphragm 112 is interposed between the casing member 105 and a cover plate 115 secured thereto by means of bolts 116, which diaphragm is exposed at the lower side thereof to the chamber 110 and has formed at the upper side thereof a chamber 117 communicating by way of a pipe 118 with the fuel supply pipe 3, as shown in Fig. 1, at a point intermediate the cut-off valve device 18 and the valve device 33. Engaging the diaphragm 112 on the lower face thereof is a follower member 120 having guide pins 121 projecting downwardly therefrom through the chamber 110 and outwardly through suitable apertures formed in the casing member 105, and also having a centrally disposed rod 123 which is slidably mounted in a suitable bore formed in the clamping member 107 and has secured to the lowermost end thereof a crosshead member 124. A coil spring 125 is interposed between the follower member 120 and the nut 111 for urging the diaphragm 112 upwardly in opposition to the pressure of fuel supplied in the chamber 117.

The crosshead member 124 is disposed at a right angle with respect to the rod 123 and is arranged within the frame 100, one arm of the crosshead member extending into alignment with the supply valve assembly 103 and the other end into alignment with the drain valve assembly 104. The crosshead member has formed thereon a central lug portion 127 which is formed as a clevis and carries a pin 128 from which is hung a vertically disposed latch member 130 having the lower end thereof slidably mounted in an opening 131 formed in the lowermost portion 102 of the frame. The latch member 130 has a surface 132 which is adapted to engage the adjacent wall of the opening 131 while the crosshead member 134 is positioned as shown in Fig. 2, and is provided with a notch or recess 133 adapted to interlock with the portion 102 of the frame upon upward movement of the crosshead member, as hereinafter explained, under the force exerted by a spring 134 attached to the frame and bearing against the latch member. The latch member 130 has a handle portion 135 for enabling manual release thereof.

The supply valve assembly 103 comprises a body 138 having a screw threaded end 139 extending through a suitable aperture formed in the frame 100 and secured thereto by means of a clamp nut 140, and having formed therein a valve chamber 141 which communicates by way of a pipe 142 with the chamber 41 of the controller device 10, and which is closed at the upper end by means of a plug element 143 having screw threaded connection with the portion 139. Disposed in the valve chamber 141 is a ball valve 145 which is engaged by a stem 146 that is slidably mounted in a suitable bore formed in the plug member 143 and extends upwardly and outwardly thereof through a suitable packing means 147. The outer end of a stem 146 is adapted for engagement with an adjustable nut 149 carried on the adjacent arm of the crosshead member 124. The ball valve 145 is adapted to engage 70 a seat 151 for controlling communication from the chamber 141 to a chamber 152 communicating with the water supply pipe 43, and is adapted to be normally maintained in seated position under the downward force of the spring 75

125 exerted through the medium of the stem 123, crosshead 124, and valve stem 146.

The drain valve assembly 104 is similar in construction to the assembly 103 and comprises 5 a body 155 having a threaded portion 156 disposed within an aperture in the frame 100 and secured in place by means of a lock nut 157. The body 155 has formed therein a valve chamber 158 containing a ball valve 159 which is 10 adapted for engagement with a seat 160 for controlling communication between the chamber and a bore 161 communicating with a drain pipe 162. The ball valve 159 is urged toward the seat 160 under the force of a coil spring 165 disposed 15 in the chamber 158, and is normally held in unseated position, as shown in the drawing, through the medium of a valve stem 166 engaging the ball valve, which stem extends upwardly through the bore 161 and suitable openings in a plug member 167 and packing 168, and into operative engagement with an adjustable nut 169 mounted on the adjacent end of the crosshead member 124.

Operation

The operation of the steam actuated controller device 10 need not be explained in detail, as the functioning of this device is well understood by those skilled in the art, complete description of the mode of operation thereof having been presented in my aforementioned Patents 2,147,294 and 2,176,132. Briefly, when a predetermined maximum pressure of steam is attained in the boiler and in the chamber 64 of the device 10 communicating therewith, the steam pressure becomes effective through the medium of the diaphragm 60 to force the follower member 67 and stem 75 downwardly against the pressure of the spring 68, thereby turning the lever 72 about the bearings 73 for actuating the stems 79 and 50 to move the ball valve 46 away from its seat. Water under pressure is then admitted from the supply pipe 43 past the unseated ball valve 46 and through the restricted passage 45 to the chamber 41 beneath the piston 20, which is thereby shifted upwardly toward its low fire position for operating the valve 33 (see Fig. 1) to restrict the supply of fuel by way of the pipe 3 and for also effecting closure of the draft door 5 and damper 7. As the piston 20 is moved upwardly, the rods 93 and 91 carried by the piston stem 22 are moved in the same direction, the inclined arm 91 causing operation of the bell crank lever 87 to compress the spring 83 and through the medium thereof to exert an upward force on the free end of the lever 72, until the lever is finally returned to its upper position for permitting the spring 48 to seat the ball valve 46, further movement of the elements being then stopped. It will thus be seen that the controller device 10 is operative in accordance with the pressure of steam generated in the boiler to control the furnace fire automatically.

It will be understood, of course, that when the 65 pressure of steam in the chamber 64 acting on the diaphragm 60 is again restored to the normal value, due to the reduction in the rate of steam generation caused by the operation above explained, the spring 68 will then force the follower member 67 and plunger member 75 upwardly to relieve the downward pressure on the lever 72, whereupon the spring 54 becomes effective to shift the stems 50 and 79 upwardly until the end 44 of the stem 50 is lifted out of engagement with the ball valve 46, which meanwhile en-

gages its seat. Water under pressure previously supplied to the chamber 41 is then discharged by way of the restricted passage 45 and through the passage 51 in the stem to the pipe 56, from which the water flows by way of valve chamber 158 of the auxiliary regulator device 11 and past the normally unseated ball valve 159 and through bore 161 to the drain pipe 162.

Referring again to Fig. 1, the weight 28 carried by the lever 24 then becomes effective to cause movement of the controller device 10 toward full fire position, and to turn the lever in a clockwise direction about the pin 26 for returning the valve 33 to its normal open position while effecting opening movement of the draft door 5 and of the damper 7.

Downward movement of the piston 20 as just explained is continued until the inclined rod 91 associated therewith permits sufficient clockwise rotation of the bell crank lever 87 about the pin 83 to permit release of the force exerted by the spring 83 against the lever 72, so that the spring 68 is enabled to act through the medium of the lever and the valve stems 79 and 50 to effect seating of the end of the stem 50 on the bell valve 46 to stop further draining of water from the chamber 41.

It will be understood that the various elements of the pressure generator 12, the fuel cut-off valve device 18 and the feed water valve device 14 are arranged and proportioned so that the valve device 14 will be closed and the valve device 18 opened when the pressure of the fluid maintained in the pipe 16 by the generator corresponds to the normal level of water in the boiler.

Let it now be assumed that the water in the boiler falls below the normal level, with the result that the pressure of fluid produced by the generator 12 is increased so that the feed water valve device 14 is operated to supply water to the boiler by way of the pipe 15, while the fuel cut-off valve device 18 is operated to restrict the flow of fuel to supply pipe 3 and thereby to reduce the rate of supply of fuel to the burners of the furnace 1. With the supply of fuel thus restricted, the rate of generation of steam in the boiler is consequently reduced so that the pressure of steam acting in the chamber 64 of the controller device 10 is gradually lessened, and the operating elements of the controller device are thereby conditioned for automatic movement toward full fire position as hereinbefore explained.

According to the present invention, however, such operation of the steam pressure actuated controller device 10 in response to the reduction in the supply of fuel following the low water condition in the boiler is prevented, due to operation of the auxiliary regulator device 11. When the fuel cut-off valve device 18 is automatically operated as above explained to restrict the flow of fuel to the pipe 3, the consequent reduction in the pressure of fuel in the chamber 117 communicating therewith causes upward movement of the diaphragm 112 and follower member 120 under the force of the spring 125. In so moving the follower member 120 carries with it the stem 123 and crosshead member 124. As the crosshead member 124 is moved upwardly, the spring 165 becomes effective to move the ball valve 159 into engagement with the seat 160 for cutting off the drain communication from the chamber 41 of the controller device 10 through the pipe 56, while with the ball valve

145 relieved of downward pressure the water under pressure supplied through the pipe 43 to the chamber 152 is free to flow past the ball valve and through pipe 142 to the chamber 41.

When the crosshead member 124 and associated elements are moved to the extreme upper position, the notch 133 of the latch member 130 is brought into locking engagement with the portion 102 of the frame 100 under the force of the spring 124, and automatic downward movement of the associated elements is thereby prevented.

Upon the supply of water under pressure to the chamber 41 of the controller device 10 by reason of operation of the auxiliary regulator device 11 as just explained, the piston 20 is moved upwardly, and acts through the medium of the rod 22, and the associated chain and lever elements shown in Fig. 1, to cause movement of the valve device 33 toward its closed position, and also to effect closing operation of the draft door 5 and the damper 7. The furnace 1 is thereby conditioned for low fire operation.

Upon restoration of the level of water in the boiler to the normal height, the cut-off valve device 18 is once again operated automatically to permit free flow of fuel under pressure to the supply pipe 3, so that the pressure of fuel in the chamber 117 of the auxiliary regulator device 11 is restored to the normal value. If now latch 130 is disengaged from member 102, the diaphragm 112 is then moved downwardly and through the medium of the follower member 120 and crosshead member 124 effects movement of the ball valve 145 to seated position while causing movement of the ball valve 159 away from its seat, as shown in Fig. 2 of the drawing. The supply of water under pressure through the pipe 142 to the chamber 41 of the controller device 10 is thus shut off, while the drain communication is opened to permit discharge of water therefrom by way of the restricted passage 45, past the ball valve 46, and thence by way of the passage 51, pipe 56, chamber 158 and bore 161 to the drain pipe 162. By reason of the restriction in flow of water through the passage 45, the discharge of water from the chamber 41 is effected gradually, so that the piston 20 and associated elements of the controller device 10 are slowly moved toward full fire position to prevent too rapid an increase in the supply of fuel to the furnace.

From the foregoing it will be seen that the auxiliary regulator device 11 is adapted for association with a furnace and boiler having automatic control means of the class described and is operative to prevent an increase in the rate of supply of fuel to the furnace following a restriction in the rate of supply of fuel, due to an excessive reduction in the level of the water in the boiler or otherwise, until the operator releases the latch member 130 to restore the control system to its normal method of operation. The operator thus has an opportunity to ascertain whether or not the automatic supply of water to the boiler has been accomplished before conditioning the system to increase the rate of supply of fuel to the furnace. It will be apparent that by reason of the fact that the auxiliary regulator device 11 is simply and inexpensively constructed as a unit, the device is adapted to be employed with different types of boiler control systems, and may be mounted in any suitable position without the requirement of expensive alterations in existing equipment.

Although one embodiment of the invention has been described in detail, it is not my intention to limit the invention to that embodiment or otherwise than by the terms of the appended claim.

Having now described my invention, what I claim as new and desire to secure by Letters Patent, is:

An auxiliary fuel pressure responsive regulator device adapted for association with an automatic fire and draft controller of the type actuated on an increase in fluid pressure to establish a low fire condition in a furnace, said regulator device comprising a casing having a bracket portion, a spring, a diaphragm mounted within said casing and subject to the opposing pressures of said spring and of fluid fuel supplied to the furnace, a frame member having a flange portion clamped to said casing and a flat portion spaced therefrom, a first valve assembly mounted 20 on said flat portion including a supply valve

controlling the supply of fluid under pressure to said fluid pressure actuated fire and draft controller, a second valve assembly mounted on said flat portion in spaced parallel relation with respect to said first assembly and including a release valve controlling the discharge of fluid from said controller, a yoke element operative by said diaphragm and disposed in said frame member with the ends thereof in alignment with 10 the respective valve assemblies, means cooperating with said ends of the yoke element for controlling said release and discharge valves in accordance with movement of said diaphragm, and a latch member pivotally connected to said 15 yoke element intermediate the ends thereof, said latch member being arranged for interlocking engagement with said flat portion of the frame member upon predetermined movement of the associated operating elements.

JAMES W. HARRIE.
